UNITED STATES PATENT OFFICE.

MANSFIELD C. CRAWLEY, OF GROTON, NEW YORK, ASSIGNOR TO ADDOGRAPH COMPANY, OF LOS ANGELES, CALIFORNIA, A CORPORATION OF CALIFORNIA.

TYPEWRITING MACHINE.

Application filed April 8, 1918, Serial No. 227,259. Renewed January 29, 1924.

To all whom it may concern:

Be it known that I, MANSFIELD C. CRAWLEY, a citizen of the United States, and resident of Groton, county of Tompkins, and State of New York, have invented certain new and useful Improvements in Typewriting Machines, of which the following is a specification.

This invention relates to improvements in typewriting machines and more particularly to mechanism for automatically locking the printing instrumentalities against operation after the carriage has traveled any predetermined distance in its letter-spacing movement, and means for automatically sounding an alarm as the carriage approaches the limit of the letter-spacing movement for which said locking mechanism is set.

20 The mechanism shown in the drawings is especially designed for use in connection with power-operated typewriting machines constructed as shown in my Patent No. 1,156,061, dated October 12, 1915, but it will be obvious that the invention is adapted to be used in connection with other forms of typewriting machines.

This application is subordinate to my application Serial No. 592,525, filed October 20, 1922, and allowed August 29, 1923, wherein subject matter generic to the two applications is broadly claimed.

The invention has for one of its objects the provision of simple line locking mechanism which may be set to automatically lock the platen carriage, type bars and key levers against movement when the carriage has traveled a predetermined distance in its letter-spacing movement, and to provide means operable by a key forming a part of the keyboard whereby the machine may be operated at will to write a line of greater length than that for which said locking mechanism is set.

45 A further object of the invention is to provide an indicator and actuator for a line-locking mechanism adjustable along the scale of a typewriting machine and adapted to be engaged and operated by an abutment 50 on the carriage to lock the printing instrumentalities against further operation when a line of the length for which said indicator is adjusted has been written.

Another object of the invention is to provide line locking mechanism for a power-

operated typewriting machine, adapted to hold the power releasing trip device against operation when a line of the desired length has been written.

Another object of the invention is to provide a line-end alarm for a typewriting machine, operable automatically by a preliminary movement of a line-lock mechanism to sound an alarm in advance of the locking of the printing mechanism against operation. 60

A further object of the invention is to provide a combined line locking and line-end alarm mechanism having a combined indicator and actuating device adjustable along the front of the machine in cooperation with the scale and operable by a supporting roll of the carriage. 65

In the drawings, Fig. 1 is a fragmentary vertical longitudinal sectional view of a typewriting machine provided with the improved alarm and line-locking mechanism; 70

Fig. 2 a fragmentary plan view of the machine;

Fig. 3 a detail view showing the adjustable indicator and actuator for the line-locking and alarm mechanism; 75

Fig. 4 a fragmentary vertical sectional view showing the key-operated releasing mechanism in side elevation; and

Fig. 5 a fragmentary vertical transverse 80 sectional view on the line V—V of Fig. 1.

As shown, the machine is provided with a main frame 1, key levers 2 pivotally supported on one or more transversely extending rods 3 held in the main frame, type bars 4 pivotally supported at 6 in a suitable type segment 7, and a platen 8 journaled in a suitable carriage 9. The carriage 9 may be of any suitable construction and may be supported at its rear edge in any suitable manner, to travel transversely of the main frame during its letter-spacing movement. An antifriction supporting roller 10 is journaled on a stud 11 projecting forwardly from the front rail 12 of the carriage 9, said roller being located midway the length of the carriage and adapted to travel along a track 13, held to the frame 1, to support the front edge of the carriage. 90

The type bars 4 are adapted to be moved upwardly and rearwardly toward the platen by a power-operated segmental universal actuator, such as that shown in the patent and application heretofore referred to, which actuator is adapted to engage the free rear 100 edge of the carriage. 105

Another object of the invention is to provide line locking mechanism for a power- 110

ends of arms 5 which are pivotally held at 14 to rearwardly and downwardly extending projections 15 formed on the type bars. The free rear ends of the series of arms 5 are supported on a segmental bracket or support 16 and are normally held in engagement with said bracket by springs 17. The rear ends of said arms 5 are adapted to be raised into the path of the power-operated 10 actuator by upwardly extending arms 18 pivotally connected at their lower ends at 19 with the rear ends of the key levers 2.

Each arm 5 is formed with an inclined or cam surface 20 adapted to engage a segmental universal trip bar 21 and force said bar rearwardly when the associated key lever 2 is operated. The bar 21 is rigidly held to a bar 22 which is pivotally connected at its ends at 23 with the lower ends of a pair of 20 forwardly and rearwardly swinging arms 24 pivotally held to the frame in any suitable manner. The bar 22 is connected by a link 25 with a pivoted hook or latch 26, the link 25 being pivotally connected with the 25 lower end of the hook at 27 and the hook being pivotally held at 28 to a suitable bracket 29 secured to the frame 1.

The hook 26 is adapted to engage the outer end of a crank 30, loosely mounted on 30 a constantly running motor-driven shaft 31, to normally lock the crank in the position shown in Fig. 1. The crank 30 is connected by a link, not shown, with a universal actuator, and is adapted to control said actuator 35 through a pawl 32 mounted on the crank and adapted to be moved by a cam 33 into and out of engagement with a ratchet wheel 34 fixed on shaft 31. The universal actuator is not shown as said actuator and the 40 mechanism for operating the same are constructed and operate substantially as shown and described in the patent and application heretofore referred to.

The line locking and line-end alarm mechanism shown in the drawings may be 45 adjusted to sound an alarm and lock the key levers, type bars and universal trip device against operation after a line of any predetermined length has been written. The universal trip mechanism, type bars and key 50 levers are all held against movement by a single transversely swinging latch bar 35 pivotally held intermediate its ends on a horizontal stud 36 secured to the frame 1. The lower end of latch 35 is offset rearwardly and formed with a laterally projecting portion 37 normally held out of the path 55 of hook 26 by a spring 38. A suitable stop pin 39 limits the movement of the latch 60 35 under the tension of spring 38, and said latch is adapted to be rocked about its pivot 65 against the tension of said spring by a reciprocable bar 40, the inner end of which is adapted to engage the edge of latch 35 adjacent the upper end of the latch.

The bar 40 is normally held in the position shown in Figs. 2 and 5 by a spring 41, and is adapted to be shifted toward the right-hand side of the machine by the engagement of the carriage-supporting roller 70 10 with an adjustable line-lock and alarm actuator supported at the front of the machine. The adjustable actuator comprises a sleeve 42 mounted on a shaft 43 journaled in brackets or supports 44 held to frame 1. 75 The sleeve 42 is freely slidable lengthwise of shaft 43 and is held to said shaft to rotate therewith by means of a key 42^a which is slidable in a groove 45 in said shaft. A forwardly extending arm 46 is loosely pivoted at its rear end in a groove 47 in sleeve 42 and is adapted to shift said sleeve longitudinally of shaft 43, and is also adapted to rotate on said sleeve to permit an abutment 48 on said arm to be moved into and 80 out of engagement with the teeth of a rack 49. The rack 49 is formed on the lower edge of a scale plate 50 and the teeth of said rack coincide with the graduations of the scale 50. The pivoted adjusting and locking arm 46 is provided with a pointer 51 cooperating with the scale 50, and said arm is normally forced toward the rack 49 by a spring 52 to hold the locking abutment 48 in 85 engagement with the teeth of rack 49. The rear end of spring 52 is held to sleeve 42 and the free forward end of said spring engages under the arm 46 and normally forces said arm upwardly. A rearwardly 90 extending arm 53 is rigidly held to sleeve 42 100 to rotate and slide therewith, and a cam having oppositely inclined faces 54 and 55 and an intermediate flat face 56 is rigidly supported on the rear end of the arm 53 in the path of the carriage-supporting roller 105 10, the portion 56 of said cam being normally held above the plane of the bottom of track 13, as shown in Fig. 3.

The rock shaft 43 is provided with a depending rock arm 57 rigidly held at its upper end to said shaft adjacent the left-hand end of the shaft and pivotally connected at 58 with the forward end of a link 59. The rock arm 57 extends downwardly 110 through a suitable elongated slot 60 in the frame (indicated by dotted lines in Fig. 1), and the rear end of link 59 extends upwardly and is pivotally connected at 61 with one arm of a bell-crank lever 62 pivotally held to the frame 1 at 63. The other arm of the bell-crank lever 62 has a pin-and-slot connection 64 with the left-hand end of the reciprocable bar 40.

With the construction above described it 125 will be obvious that by depressing the forward end of arm 46 the actuator may be adjusted longitudinally of rock shaft 43 until pointer 51 registers with the desired graduation on scale 50, and that when said arm 46 is released the spring 52 will hold 130

the locking abutment 48 in engagement with rack 49, and thus lock the actuator in its adjusted position. As the carriage 9 approaches the limit of the letter-spacing 5 movement for which the actuator is set the roller 10 will ride over the long inclined face 54 of the cam on arm 53 of the actuator, thus gradually rocking shaft 43 and arm 57 and pulling link 59 forwardly. 10 Owing to the lost motion in the pin-and-slot connection 64 the initial downward movement of the cam and arm 53 and the forward movement of link 59 does not effect bar 40. This initial movement of the actuator however, causes a pawl 65 pivotally held on link 59 to engage the upwardly extending arm 66 of a bell clapper 67 and rock said clapper about its pivot 68 away from an alarm bell 69. The clapper is pivoted to a bracket 70 held to frame 1 and is normally forced toward the bell by a spring 71, and it will be obvious that as pawl 65 is pulled forwardly it will first depress the clapper 67 and then release the same, whereupon the spring 71 will cause the clapper to strike the bell 69, thus sounding an alarm to warn the operator that the carriage is approaching the limit of its travel.

20 A further movement of the carriage will carry the roller upon the flat or highest surface 56 of the cam, thus pulling link 59 forwardly to a greater extent and causing the bell-crank lever 62 to force the bar 40 toward the right-hand side of the machine. It will be seen that this movement of bar 40 will rock the latch 35 and force the projecting lower end 37 thereof behind the trip latch 26, thus preventing rearward movement of said latch 26, link 25, bar 22 and the universal trip bar 21, and locking the trip bar and type bars against operation. It will be observed also that the trip bar 21 will prevent upward movement of the type bar operating arms 5 and the arms 18, thus locking the key levers against operation.

25 To permit the operator to operate the machine to write additional characters or words upon the same line at will, I have provided means for releasing the line-locking mechanism, operable by a key 72 forming a part of the keyboard of the machine. The key 72 is supported on the forward end of a key lever 73 pivotally mounted on one of the transverse pivot rods 3 which support the printing keys. A vertically reciprocable arm 74 is pivotally connected at 35 with the release key lever 73, and its upper end is slidably held in a suitable guide 76 held to the frame 1. The upper end of the vertically movable arm 74 is beveled at 77 and is adapted to engage the rear edge of the right-hand end of a horizontally swinging lever 78. The lever 78

30 is pivotally held intermediate its ends to the frame 1 on a depending stud or pivot pin 79, and has a pin-and-slot connection 80 at its inner or left-hand end with the adjacent end of bar 40.

35 By depressing the releasing key 72 the operator may shift latch 35 out of the path of the trip hook 26, thus permitting further operation of the printing instrumentalities to write additional characters or words upon the same line after said instrumentalities have been locked against operation by the automatic line-locking mechanism. It will be obvious that when key 72 is depressed, arm 74 will be lifted and the cam edge 77 thereof will rock lever 78 and force the end of bar 40 rearwardly past the edge of latch 35, thus permitting spring 38 to pull the lower offset end 37 of said latch from behind the hook 26. The inclined face 55 of the line lock actuator permits the carriage to be readily returned to the right-hand side of the machine if the machine is operated subsequently to release of the line lock mechanism by key 72, sufficiently to cause the roller 10 to pass to the left of the actuator.

40 What I claim is:

45 1. In a typewriting machine having a source of power and a universal power-operated type-bar actuating device, the combination of type-bar selecting means, a latch normally locking the type-bar actuating device against movement, means for releasing said latch upon the selection of a type-bar by the type-bar selecting means, a traveling platen carriage, a stop member, and mechanism operable automatically upon movement of the carriage to a predetermined point to shift said stop member into engagement with said latch to prevent release of the latch by said latch-releasing means.

50 2. In a typewriting machine having a source of power and a universal power-operated type bar actuating device, the combination of type-bar selecting means, a latch normally locking the type-bar actuating device against movement, means for releasing said latch upon the selection of a type-bar by the type-bar selecting means, a traveling platen carriage, a stop member, mechanism operable automatically upon movement of the carriage to a predetermined point to shift said stop member into engagement with said latch to prevent release of the latch by said latch-releasing means, a release key, and connections between said key and said mechanism for disengaging said stop and latch upon operation of said key.

55 3. In a typewriting machine, the combination of a frame, a platen carriage mounted on rollers, a rock shaft extending transversely of the frame, a line lock trip 60 slidably held to said shaft and adapted to

70

rock the same when depressed, printing mechanism, line lock mechanism operatively connected with said rock shaft and adapted to prevent operation of the printing instrumentalities when the trip is depressed, the trip and carriage being relatively so positioned that the carriage in its letter-spacing movement transversely of the frame causes one of its rollers to depress said line lock trip.

4. Line-locking mechanism for typewriting machines having a traveling platen carriage, comprising a member shiftable from a normal inactive position to an active position preventing printing, an endwise and laterally shiftable bar independent of said member, means operable upon movement of the carriage to a predetermined point for shifting said bar endwise to cause the same to move said member to its active position, a release key, and connections between said key and said bar for shifting the bar laterally to release said member to permit said member to return to normal, inactive position irrespective of the position of the bar.

5. In a typewriting machine, the combination of a frame, a rock shaft extending transversely of the frame, a carriage-supporting track extending transversely of the frame adjacent said rock shaft, a platen carriage having a supporting roller adapted to travel upon said track, printing mechanism, a line locking device operatively connected with said rock shaft and adapted to prevent operation of the printing mechanism, and a rock arm adjustable longitudinally of said rock shaft having its free end extending in the path of said carriage-supporting roller and adapted to rock said shaft when its free end is depressed by said roller.

6. In a typewriting machine, the combination of a frame, a rock shaft extending transversely of the frame, a carriage-supporting track extending transversely of the frame adjacent said rock shaft, a platen carriage having a supporting roller adapted to travel upon said track, printing mechanism, a line locking device operatively connected with said rock shaft and adapted to prevent operation of the printing mechanism, a rock arm adjustable longitudinally of said rock shaft having its free end extending in the path of said carriage-supporting roller and adapted to rock said shaft when its free end is depressed by said roller, means for locking said rock arm in its adjusted position, and key-operated means for releasing said line locking device.

7. Line-locking mechanism for typewriting machines having a traveling platen carriage, comprising a pivotally supported locking member adapted to prevent operation of the printing means, a spring normally holding said member out of locking position, a

bar independent of said locking member, an adjustable carriage-operated trip, connections between said trip and said bar for shifting the bar endwise transversely of the pivotal axis of the locking member to rock 70 said member to locking position, and manually operable means for shifting said bar laterally relatively to the locking member to release said member.

8. In a typewriting machine, the combination of a frame having a scale-carrying bar at the front thereof, a downwardly-facing rack held to said scale-carrying bar, a carriage movable transversely of the frame, printing mechanism, a line locking 80 device adapted to prevent operation of the printing mechanism, a line-end alarm bell, a bell clapper, a trip device mounted on the frame and adjustable longitudinally of the scale-carrying bar, a spring-pressed 85 latch pivotally held to said trip device and adapted to normally swing up and engage the teeth of said rack to lock the trip device in its adjusted position, a pointer carried by said latch extending upwardly in 90 front of said scale bar, means movable with the carriage adapted to actuate said trip device, an operating connection between said trip device and said line locking device, and means carried by said operating connection 95 adapted to operate the bell clapper in advance of the operation of the line locking device.

9. In a typewriting machine, the combination of a frame, a carriage movable transversely of the frame, a line-end alarm bell, a bell clapper, power-actuated printing mechanism embodying a release trip, a line locking device adapted to prevent operation of the printing mechanism by locking said release-trip, a trip adjustably mounted on the frame and operable by the carriage, and operating connections between said trip and the bell clapper and line locking device adapted to actuate the bell clapper and line-locking device in succession.

10. In a power-operated typewriting machine, the combination of a frame, a carriage-supporting track, a carriage having a supporting roller traveling on said track, a rock shaft supported on the frame parallel with said track, a rock arm adjustable along said shaft and adapted to rock the same and having a cam portion normally extending in the path of said roller, type bars, a trip device operable to permit power mechanism to actuate the type bars, a line lock device adapted to hold said trip device against movement, and an operating connection between said rock arm and said line lock device adapted to shift said line lock device to locking position when the rock arm is depressed by the carriage-supporting roller.

11. In a power-operated typewriting machine, the combination of a frame, a car-

riage-supporting track, a carriage having a supporting roller traveling on said track, a rock shaft supported on the frame parallel with said track, a rock arm adjustable along 5 said shaft and adapted to rock the same and having a cam portion normally extending in the path of said roller, type bars, key levers, a universal trip device operable by the key levers to permit power mechanism 10 to actuate the type bars, a pivoted latch adapted to hold said trip device against movement, an operating connection between said rock arm and said latch adapted to shift the latch to locking position, and a 15 spring normally holding said latch out of locking position.

12. In a power-operated typewriting machine, the combination of a frame, a carriage-supporting track, a carriage having a 20 supporting roller traveling on said track, a rock shaft supported on the frame parallel with said track, a rock arm adjustable along said shaft and adapted to rock the same and having a cam portion normally extending in 25 the path of said roller, type bars, key levers, a universal trip device operable by the key levers to permit power mechanism to actuate the type bars, a pivoted latch adapted to hold said trip device against movement, an operating 30 connection between said rock arm and said latch adapted to shift the latch to locking position, a spring-normally holding said latch out of locking position, a release-key lever forming a part of the keyboard, and an operating connection between said 35 release-key lever and the latch-operating connection for releasing the latch.

13. In a power-actuated typewriting machine, a locking device for preventing power 40 being applied to the printing devices, mechanism operated by an adjustable margin stop for shifting said device into locking position and holding it there, said mechanism embodying an endwise reciprocable

bar adapted to engage the locking device 45 and push it into locking position, and independent key-operated devices for shifting this bar laterally out of engagement with the locking device to permit the locking device to assume a non-locking position, for 50 the purpose set forth.

14. Line-locking mechanism for typewriting machines having a traveling platen carriage, comprising a member shiftable from a normal inactive position to an active position preventing printing, an endwise and laterally-shiftable bar independent of said member, means operable upon movement of the carriage to a predetermined point for shifting said bar endwise to cause the same 60 to move said member to its active position, a release key, and connections between said key and said bar for shifting the bar laterally to release said member to permit said member to return to normal inactive position irrespective of the position of the bar. 65

15. Line-locking mechanism for typewriting machines having a traveling platen carriage, comprising a pivotally-supported locking-member adapted to prevent operation of the printing means, a spring normally holding said member out of locking position, a bar independent of said locking-member, an adjustable carriage-operated trip, connections between said trip and said 70 bar for shifting the bar endwise transversely of the pivotal axis of the locking-member to rock said member to locking position, and manually-operable means for shifting said bar laterally relatively to the 75 locking member to release said member and thus permit it to instantly return to inactive position irrespective of the position of the bar. 80

This specification signed this 4th day of 85 April, A. D. 1918.

MANSFIELD C. CRAWLEY.
